(57) **CLAIM**

What is claimed is the ornamental design for a paint overspray guard, as shown and described.

DESCRIPTION

FIG. 1 is a perspective view of a paint overspray guard, showing the new design;

FIG. 2 is a front elevational view thereof;

FIG. 3 is a top plan view thereof, the bottom plan view being a mirror image thereof;

FIG. 4 is a rear elevational view thereof;

FIG. 5 is a right-side elevational view thereof; and,

FIG. 6 is a left-side elevational view thereof.

The broken lines showing text and images applied to the surface of the design in FIGS. 1 and 2 are environmental and form no part of the claimed design.
